UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPE OR MATRIX.

1,151,619.

Specification of Letters Patent. Patented Aug. 31, 1915.

Original application filed August 22, 1913, Serial No. 786,083. Divided and this application filed March 31, 1914. Serial No. 828,438.

To all whom it may concern:

Be it known that I, JOHN R. ROGERS, a citizen of the United States, residing at Brooklyn, in the county of Kings and State 5 of New York, have invented certain new and useful Improvements in Type or Matrices, of which the following is a specification, reference being had therein to the accompanying drawing.

10 My invention relates to type or matrices, and more particularly to that kind employed in machines of the character illustrated in my U. S. Letters Patent No. 679,481, dated July 30th, 1901. In this class of machines, 15 the matrices are suspended from a series of endless inclined guides, and the parts are so arranged that the individual matrices released by finger keys descend by gravity along converging portions of the guides to 20 the assembling point, whence they are carried by a traveling finger to the casting mechanism, and thence upward to the rear end of the machine, where they descend along diverging portions of the guides to 25 their original places thereon. Ordinarily in these machines there are as many guides as there are characters represented in the keyboard, a group of matrices bearing the same characters traveling upon each guide.

30 It is one of the objects of my present invention to provide for the travel of matrices bearing different characters upon the same guide, so that the number of guides in the machine may be materially reduced, and I 35 therefore provide a group of matrices for each guide, but divide each of such groups into subgroups containing different kinds of matrices, making those of one subgroup of different form from those of another, so that 40 they may be properly separated and returned to their different places of storage.

In the specific embodiment shown, in addition to the ordinary hooks by which they are suspended, I have provided all the matrices if the subgroups, except one, with further hooks, which are located in different vertical positions on the matrices in respective subgroups, and which are adapted to co-operate with mechanism of suitable character to effect their separation. Such a mechanism may be found in my pending application for Letters Patent, Serial No.

786,083, filed August 22nd, 1913, of which the present case is a division.

A further object of my invention is to 55 improve the form of the individual matrices without regard to group or subgroup, so as to adapt them to travel upon the guides with greater ease and with less liability to disengagement therefrom.

60 Other objects and the manner in which they are accomplished will be more fully pointed out in the detailed description to follow.

The drawing shows matrices of various 65 groups and of different form to distinguish them as to subgroups, etc.

Referring to the drawing, the matrices are of the usual elongated form, each being formed in one of its edges with the 70 intaglio characters Y^1 , wherein the type letters are cast, and in its opposite edge with a corresponding plurality of notches Y by which their vertical alinement is effected. The matrices are further formed in their 75 lower ends with notches Y^5 to receive a stationary plate during their passage from one point to another in the machine, the plates serving to prevent the twisting or turning of the matrices upon the guides. So 80 far as described the matrices are of the ordinary construction.

Each of the matrices is also formed at its upper end, as usual, with a hook Y^3 by which it is suspended. However, according 85 to my present invention, I have offset this hook laterally or rearwardly from the body of the matrice, as shown at the extreme left of the drawing, the purpose being to permit a greater freedom of movement of the 90 matrices upon the guides without the consequent danger of becoming disengaged therefrom.

A further feature of my invention consists in the formation of a notch Y^2 in the 95 upper end of each matrix to receive a guard member overlying the guide upon which the matrix travels, this member serving to prevent the detachment of the matrix from or its improper shifting upon the guide, which 100 is apt to occur especially at the point of convergence of the guides, where the inclination is considerable.

In the drawing I have shown eight groups

of type or matrices, X^1 , X^2 , X^3 , etc., the matrices being of different lengths in the different groups, but of the same length in the same group, all as will be familiar to those skilled in the art. Each group is shown as divided into six subgroups, all provided with the suspending hooks Y^3 , but of different form otherwise in respect of subgroup. For instance, five of the subgroups of group X^1 are formed each with a single separating hook Y^4 , these hooks being located in different vertical positions on the matrices in the respective subgroups, as indicated by full and dotted lines, and the sixth subgroup being without a separating hook. In this way, the matrices of the several subgroups may be separated from each other and delivered to their proper places of storage. The six subgroups of the matrices X^2 are also constructed in the same manner, five with differently located hooks Y^4 and one without the hook, all six being provided with the suspending hook Y^3 . Each group of matrices X^3 , X^4 , X^5 , X^6 , X^7 and X^8 is similarly formed, all of them with suspending hooks, and five subgroups with separating hooks and one subgroup without a separating hook, although for the sake of simplicity of illustration the matrices of the subgroups without separating hooks are not shown.

While I have illustrated my invention as applied to the particular kind of matrices described, it will be understood that it is capable of application to other kinds, and also to type or dies, and further, may be embodied in different form from that shown and described. Generally speaking, I do not desire to limit myself to any particular form or adaptation except in so far as the scope of the appended claims require it.

Having thus described my invention, its construction and mode of operation, what I claim and desire to secure by Letters Patent of the United States, is as follows:

1. A type or matrix adapted to travel along a guide or wire, and formed with a suspending hook to support it in its travel, the said hook being offset laterally with respect to the plane of the body portion of the type or matrix to insure its engagement with the guide.

2. A type or matrix provided with a hook-shaped suspending element overhanging its edge to support it during its travel, and formed in its upper end with an open vertical notch adapted to engage a guide during the travel of the type or matrix and while it is supported by its hook-shaped suspending element.

3. A type or matrix provided with a hook-shaped suspending element to support it during its travel, and formed in each end with an open elongated notch adapted to engage a guide during the travel of the type

or matrix while it is supported by its hook-shaped suspending element.

4. A type or matrix provided with a suspending hook offset laterally with respect to the plane of body portion and formed with an elongated notch in its upper end.

5. A type or matrix formed with a suspending hook, and further with a separating hook projecting from and overhanging one of its vertical edges, the former hook adapted to support the type or matrix in its normal travel, and the latter adapted to effect its separation from other type or matrices.

6. A group of suspended type or matrices of the same length, the said group comprising subgroups, the type or matrices of each subgroup being formed with a suspending hook, and further with an overhanging separating hook, and the separating hooks of one subgroup being located upon the type or matrices in a different vertical position from those of another subgroup.

7. A group of type or matrices, the said group comprising subgroups wherein each type or matrix is provided with a suspending hook, and further with a separating hook projecting from and overhanging one of its vertical edges, the former hook adapted to support the type or matrix in its normal travel, and the latter hook adapted to effect its separation from type or matrices of the other subgroups.

8. A group of suspended type or matrices of the same length, the said group comprising subgroups, the type or matrices in each subgroup being each formed with a suspending hook, and further with a separating hook, and the separating hooks being of the same character for the matrices of the entire group but located in different vertical positions on the matrices in the respective subgroups.

9. A group of suspended type or matrices, the said group being divided into subgroups, and those of one subgroup being provided only with a suspending hook, and those of the remaining subgroups being provided with a suspending hook and an overhanging separating hook projecting from one of their vertical edges for the purpose described.

10. A type or matrix formed on one of its vertical edges with a suspending hook, and on its opposite vertical edge with a separating hook, the former hook adapted to support the type or matrix in its normal travel, and the latter adapted to effect its separation from other type or matrices.

11. A group of suspended type or matrices, the said group comprising subgroups, the type or matrices of each subgroup being formed on one of their vertical edges with a suspending hook, and on the other of their vertical edges with a separating hook, and the separating hooks of one subgroup being located upon the type or mat-

rices in a different vertical position from those of another subgroup.

12. A group of suspended type or matrices each provided on one of its vertical edges with a suspending hook, the said group being divided into subgroups, and the type or matrices of one subgroup being provided only with a suspending hook, and those of the remaining subgroups being

provided on their opposite vertical edges 10 with separating hooks which effect their separation as to subgroup.

In testimony whereof I have affixed my signature in presence of two witnesses.

JOHN R. ROGERS.
